COMBINATION WINDOW STRUCTURE

Andrew Mihok, Windsor, Ontario, Canada

Application March 12, 1953, Serial No. 341,871

3 Claims. (Cl. 20—53)

This invention relates to windows and is more particularly concerned with window construction wherein the sash is mounted for rotation.

In its more specific phases the invention contemplates a sash rotatably mounted in a frame, whereby the sash may be rotated through 360 degrees of arc for washing the window pane or panes, or for providing ventilation.

The invention is also concerned with locking and sealing means for locking the sash in a closed position and for sealing it against the weather. Preferably the sash will be pivoted in the window frame along a medial horizontal line, although rotation about a medial vertical line also is contemplated.

A further object of the invention is a locking and sealing mechanism for the sash cooperating with all four edges thereof, but releasable by a single manual operating member when the sash is to be rotated for cleaning or providing ventilation.

Yet another object of the invention is a releasable locking and sealing mechanism for the sash which cannot be released from the exterior side of the sash, but which is readily releasable by a single manual operating member disposed on the interior side of the sash.

The invention is particularly applicable to large horizontally disposed or picture windows which heretofore could not be opened for ventilation.

With these and other objects in view which may appear while the description proceeds the invention consists in the novel arrangement of cooperating parts shown in the accompanying drawings forming part of this application and in which:

Figure 1 is a perspective view of one embodiment of the invention showing a single sash rotatably mounted in a frame;

Figure 2 is a typical transverse section of this embodiment showing the sash in a closed position;

Figure 3 is a section taken along the axis of rotation of the sash, but on a larger scale;

Figure 4 is a partly diagrammatic part view similar to Fig. 2, showing the sash in an almost closed position and upper locking means for the sash, and

Figure 5 is a schematic view of the releasable locking and sealing mechanism for the sash.

The invention here is illustrated with the sash adapted for opening inwardly at its bottom, although the invention also contemplates a sash opening inwardly at the top, this being effected by simply reversing the relative position of the locking mechanism in the frame.

In the drawings, wherein like characters of reference denote the same parts throughout, the numeral 10 represents a window frame which is fabricated in more or less usual manner of wood or metal stock. A sash 11 is so mounted in the frame 10 that it is rotatable about a medial horizontal axis as shown in Fig. 1, this mounting being effected by suitable pivot pins 12 disposed on opposite vertical edges of the sash, which pins cooperatively engage suitable bores or bearings 13 formed in or secured in opposite vertical sides of the said frame.

2

The glass pane 14 is carried directly by the sash, although the glazing may be subdivided into smaller panes or lights by the usual muntins, if desired.

The body of the sash 11 is formed of four rails constituting its respective sides, top, and bottom, the rails being mitered or suitably joined at the corners, and rabbed to receive the pane 14. Preferably the rails are fabricated from wood stock having one more or less rounded edge, but it is contemplated that extruded metal stock will be required in sashes of large size.

The frame 10 may be of any suitable cross section and material, but, in the form shown, is built up of four wood members constituting its respective sides, sill, and top, these members being joined in usual fashion at the corners.

Each side of the frame 10 is formed with a longitudinal groove or rabbet 15 for the reception of sash sealing strips 16 which also act as locking means which are held in position by means shortly to be described. The inner surface of each sealing strip is normally in contact with the outer faces of the side rails of the sash when the sash is in a closed position.

In like manner the sill and top of the frame 10 are formed respectively with a longitudinal groove or rabbet 17 and 18 for the reception of sash locking strips 19 and 20, which strips are held in position by means to be described. The outer surface of the locking strips 19 and 20 are normally in contact with the inner faces of the top and bottom rails of the sash 11 when the sash is in a closed position.

The sealing strips 16 are disposed in the grooves 15 in the sides of the frame 10 for limited sliding movement in and out of the grooves, and normally are urged to an outwardly position by tensed expandable elastic members which may be coil springs as at 21, and which are disposed in the grooves 15 and beneath the sealing strips 16. The said sealing strips may be made of metal, but preferably, as shown, are wood bars formed with outer rounded corners.

The locking strip 19 is formed similarly to the sealing strips 16 and is similarly disposed in the groove 17 which extends across the sill of the frame 10, being urged outwardly by other tensed expandable elastic members such as the coil springs 22.

The locking strip 20 is disposed in the groove 18 formed in the top of the frame, for limited sliding movement in and out of the groove, being urged outwardly by tensed expandable elastic members, e. g.—coil springs 23, as hereinbefore set forth for the sealing strips 16.

The locking strip 20 may be made of metal, but, as shown is a wood bar formed in more or less wedge shape, the butt of the wedge being normally in contact with the top rail of the sash 11. The locking strip 20 preferably is provided with an upper flange (not shown) and is secured by a slotted plate (also not shown) countersunk into the top of the frame 10, the said flange taking up on the upper side of the said plate when the locking strip is in the most outwardly position.

The locking strip 19 is operatively connected to each of the sealing strips 16, preferably by lengths of corrosion-resisting steel wire or cable 24, but other materials may be provided. The wires 24 pass through bores formed in the frame 10, pass over a plurality of sheaves 25 which are carried in a plurality of suitable brackets 26 attached on opposite sides of the frame, pass again through other bores in the frame 10, and are connected more or less medially of the sealing strips 16 in a manner such that the locking strip 19 and sealing strip 16 are normally in a most outwardly disposition in the grooves 17 and 15 respectively.

The fitting of the sealing strips 16 into the grooves 15

serves the two-fold purpose of locking the sash 11 against rotation and effecting a weather seal between the sash and the frame 10, while the fitting of the locking strips 19 and 20 respectively into grooves 17 and 18 permit a direction of rotation of the sash such that it can be opened only from one side, i. e.—the inner side of the sash.

Sealing of the top and bottom rails of the sash 11 against the weather is effected by fitting rain deflectors to opposite sides of the said rails as at 27. The deflectors 27 preferably are fabricated of a yieldable material, e. g.—rubber, to closely engage adjacent portions of the frame 10 while still permitting free movement of the said deflectors over the said sealing and said locking strips.

The construction of the window is such that the need for the usual locking means is obviated but other hardware, e. g.—hand pulls 28, are attached to the top and bottom rails of the sash 11 for opening and closing the sash. A cover 29 is provided for the sheaves 25 being attached to the sides of the frame 10 by suitable fasteners.

When it is desired to open the sash for cleaning or to provide ventilation, the locking strip 19 is pushed downwardly into the groove 17 in the sill of the frame, thereby tensing the steel wires 24 and causing the sealing strips 16 to be drawn into the grooves 15 in the sides of the frame 10. The sash 11 may then be pulled inwardly at the bottom (by grasping the hand-pull 28) to any desired position, being frictionally held in the selected position by the outward pressure exerted by the sealing strips 16 on the side rails of the sash, when the locking strip 19 is released. This pressure is imparted to the sealing strips, of course, by untensing of the coil springs 21, 22 and 23. Closing of the sash is effected by further rotating the frame through a total arc of 180 degrees whereupon the locking strip 20 is wedged home into the groove 18 by the passing top rail of the sash until the sash is caused to assume a vertical position in the frame. The inwardly acting pressure of the sash 11 on the sealing strips 16 and locking strip 20 then being relieved, the said strips return to the normal disposition thus effectively locking the sash 11 in a closed position. It is evident that rotation of the sash will be unidirectional at all times and that the sash may be passed through a full 360 degrees of arc, in 180 degree steps. A fully rotary window, unlockable from the outside, thus is provided.

It is believed that the construction and advantages of the structure shown may be apparent from the foregoing paragraphs taken in conjunction with the accompanying drawings without further detailed description.

While the preferred embodiment of the invention has been disclosed it is understood that minor changes in the construction, combination and arrangement of cooperating parts may be resorted to within the scope of what is claimed without departing from the spirit of the invention.

I claim:

1. A window construction comprising a frame, a sash

rotatably mounted in the said frame, the said sash being formed with four rails constituting its respective sides, top and bottom, longitudinal grooves formed in opposite sides of the said frame exteriorly of the said sash, a sealing bar disposed in each of said grooves and movable reciprocally in and out thereof, the said sealing bar having a weather sealing engagement with the side rails of the said sash, longitudinal grooves formed in the sill and top of the said frame interiorly of the said sash, a lower locking bar disposed in the groove in the said sill for reciprocating movement in and out of the last said groove and having a sealing engagement with the inner side of the bottom rail of the said sash, an upper locking bar disposed in the groove in the top of the said frame for limited reciprocating movement in and out of the last said groove, the said upper locking bar being formed as a wedge with the butt end thereof having a sealing engagement with the inner side of upper rail of the said sash, a plurality of tensed coil springs disposed in the said longitudinal grooves and urging the said sealing bars, said lower locking bar and said upper locking bar outwardly of the said longitudinal grooves, and flexible members operatively connecting the said lower locking bar to the said sealing bars for laterally displacing the said sealing bars consequent on a lateral displacement of the said lower locking bar to release the said sash for rotation.

2. A window construction comprising a frame, a sash rotatably mounted in said frame, longitudinal grooves formed in the sides and sill of said frame, sealing bars slidably mounted in the grooves in the sides of said frame for movement into sealing engagement with the outer side of the sash rails when said sash is closed, a locking and sealing bar slidably mounted in the groove of the sill of said frame for movement into sealing engagement with the inner side of the sash rail when the sash is closed, spring means normally projecting said sealing bars and said locking and sealing bar outwardly from said grooves, and flexible means connecting said locking and sealing bar with said sealing bars for retracting said sealing bars when said locking and sealing bar is depressed to release said sash for rotation.

3. A window construction of the character described in claim 2 wherein said flexible means is a cable extending from the ends of said locking and sealing bar around one end of each sealing bar and connects to an intermediate part of each sealing bar whereby said sealing bars are retracted when said locking and sealing bar is depressed to release the sash for rotation.
